UNITED STATES PATENT OFFICE

FRANZ J. WOOD, OF DES MOINES, IOWA

CONVEYER

Application filed November 7, 1927. Serial No. 231,667.

The object of my invention is to provide a flexible endless conveyer of simple, durable and inexpensive construction, and which is particularly adapted to be used on the feeding mechanism of threshing machines employing improved cleats for engaging the material to be fed to the threshing machine.

More specifically it is the object of my invention to provide an endless conveyer web having improved cleats which may be easily and quickly attached, and when attached are firmly secured in position and designed to be made of light material such as wood.

A further object is to provide in connection with the cleats, improved means for strengthening the cleats, and at the same time providing means for engaging and gripping the material to be carried by the conveyer.

My invention consists in the construction, arrangement and combination of the various parts of the device, whereby the objects contemplated are attained, as hereinafter more fully set forth, pointed out in my claim, and illustrated in the accompanying drawings, in which:

Figure 1 is a longitudinal sectional view of the feed trough of a band cutter and feeder showing the manner in which my improved conveyer is mounted therein.

Figure 2 is a plan view of the conveyer cleat.

Figure 3 is a sectional view taken on the line 3—3 of Figure 2.

Figure 4 is an enlarged, detail, sectional view taken on the line 4—4 of Figure 3.

Figure 5 is an enlarged, detail, sectional view taken on the line 5—5 of Figure 3.

Figure 6 is a perspective view of one of the attachment links of the endless sprocket chains for securing the cleats and the conveyer web in position relative to said chains.

The numeral 10 indicates the feed trough of a band cutter and feeder, and 11 the bottom of the platform of said trough. The trough is provided with transversely arranged shafts 12 and 13, each of which has a pair of sprocket wheels 14 and 15. Each corresponding set of sprockets 14 and 15 is provided with a sprocket chain 16 designed

to travel adjacent to each side edge of the platform 11.

Supported between the chains 16 is an endless conveyer web 17 preferably constructed of canvas or similar material, the width of the web 17 being slightly less than the distance between the chains 16. The web 17 is provided with a series of transversely arranged cleats, each of which comprises an outer slat 18 and an inner slat 19, said slats being preferably formed of wood and supported opposite and adjacent to the web 17 extending between them. The slats 18 and 19 are provided with openings 20 and 21, which are in alinement with each other, the said openings being designed to receive bolts 22 for clamping the slats to the webbing, and suitable openings being provided in the webbing for receiving the bolts. The ends of the cleats are provided with attachment links 23 connected in the chain 16 in the usual manner. Each of said attachments comprises a flat thin plate 24 having its front and back edges provided with upwardly extending flanges 25 and an opening 26. The plate 24 is designed to be supported between the adjacent ends of the slats 18 and 19 with the bolt 20 extending through the opening 26 in the manner clearly illustrated in Figures 4 and 5. Thus means is provided for firmly clamping the attachments to the cleats and the web 17.

The outer surface of the slat 18 is provided with a thin metal plate 27 provided with openings 28 for receiving the bolts 22. The front edge of the plate 27 is bent upwardly and projected forwardly beyond the front edge of the slat to form a toothed portion 29. The said member 29 has a series of triangularly shaped notches cut therein to form suitable teeth, as illustrated in Figures 2 and 3.

By this arrangement it will be seen that I have provided a conveyer especially adapted to be used in the feed trough of a band cutter and feeder. The chains 16 and the sprockets 14 and 15 provide means whereby the conveyer will be positively driven as the said sprockets are rotated, while the web 17 provides means for supporting the straw and

any shelled or threshed grain. The cleats support the web and also provide means for preventing the straw from slipping on the web. The sheet metal plates of the cleats provide means for reinforcing the cleats, and at the same time provide necessary means for engaging the straw.

On account of the cleats being formed of two slats placed on opposite sides of the web and bolted together by means of the bolts 28, means is provided whereby the web will be firmly anchored to said cleats to prevent pulling loose, due to the weight of the material thereon.

Another advantage of my device lies in the fact that if any of the conveyer slats should become broken, they may be easily and quickly replaced by removing the nuts from the bolts 28, after which the broken slats may be detached and new ones substituted.

I claim as my invention:

A conveyer cleat comprising a pair of adjacent slats and a plate adjacent to the outer face of one of said slats, one edge of said plate extending beyond and outwardly from said slats, said outwardly extending edge having a series of V-shaped notches to form teeth, bolts for clamping said plate and slats together.

Des Moines, Iowa, October 26, 1927.

FRANZ J. WOOD.
